(57) **CLAIM**

The ornamental design for an eyeglass case, as shown and described.

DESCRIPTION

FIG. 1 is a perspective view of the eyeglass case showing my new design with the case closed;

FIG. 2 is a perspective view showing the eyeglass case when open;

FIG. 3 is a top plan view of FIG. 1;

FIG. 4 is a front elevational view of FIG. 1;

FIG. 5 is a rear elevational view of FIG. 1; and,

FIG. 6 is a side elevational view of FIG. 1, the opposite side being a mirror image.

The interior surfaces that are not shown, form no part of the claimed design.
